(57)

CLAIM

The ornamental design for industrial robot module, shown and described.

DESCRIPTION

FIG. 1 is a perspective view showing the front, left side and top of my new design for an industrial robot module.

FIG. 2 is a top view thereof;

FIG. 3 is a bottom view thereof;

FIG. 4 is a left view thereof;

FIG. 5 is a right view thereof;

FIG. 6 is a rear view thereof; and,

FIG. 7 is a front view thereof.
